UNITED STATES PATENT OFFICE

2,002,469

COLUMN CLAMP FOR RADIAL DRILLS

Jack C. Carlton, Cincinnati, Ohio, assignor to
The Carlton Machine Tool Company, Cincinnati,
Ohio, a corporation of Ohio

Application September 2, 1933, Serial No. 688,008

21 Claims.

(Cl. 77—28)

My invention is exemplified in a radial drilling machine.

It is the custom of the operator of drilling machinery having a swingable arm provided with a spindle slide, to adjust the arm and the slide so that the point of the drill secured to the spindle is coincident with the point on the work with which the point of the drill is to co-operate. Such machines employ a clamp for fixing the drill-arm in adjusted position.

Radial drills usually employ a rotatable column upon which the drill-arm is adjustable to elevation and which is rotatable when swinging the drill-arm to various radial positions, the clamp 15 for clamping the drill-arm in radial position being usually at the lower end of the rotatable column.

In structures of this character now in general use the clamping of the rotatable support results 20 in rotative urge upon the rotatable column or arm, or part being clamped, with the result of change in adjusted position of the adjusted part, instanced as the point of the drill, with relation to the point on the work with which it is to co-act, caused by the clamping.

In other words, when the operator clamps the drill-arm after adjustment, he disarranges the adjustment to the extent that the point of the drill no longer registers with the point on the work with which it is to coact in the drilling operation.

The effective positioning of the part adjusted has, therefore, heretofore been largely guesswork, the operator in his adjustment of the point of 35 the drill approximating the distance to which the drill point would shift in clamping the drill-arm, and setting the drill-point accordingly. This shifting varied with the extent to which the clamp bearing had been relieved for permitting 40 swinging of the drill-arm, and with the distance lengthwise of the drill-arm to which the drill-slide had been shifted for positioning the drill, and other factors not necessary to mention, so that the conditions present for various adjustments varied, and the operator had no guidance 45 or certitude of the ultimate position of the drill-point after adjustment and clamped relation of the drill-arm.

It is the practice when employing clamping means for a rotatable sleeve or column comprising clamping cheeks and means for clamping said cheeks against a coacting member, to form the coacting clamping faces as nearly concentric as possible. The clamping cheeks are usually integral at their outer ends with the sleeve or column

and separated at their sides and inner ends from each other and from the sleeve or column, and are usually resilient and sufficiently normally free from the coacting clamping member to permit rotation between the sleeve or column and its coacting member when the cheeks are in unclamped relation.

The sleeve and cheeks are usually castings of gray iron and the clamping force exerted is great to spring the cheeks into clamped relation.

The movements of the clamping cheeks toward and from the coacting member are small, but I have found that in practice there is unevenness or dissimilarity in contact or coaction between the respective cheeks and the coacting member, which is inherent in the mechanism despite the greatest care and accuracy in manufacture. This unevenness or dissimilarity in contact or coaction results in shifting between the sleeve and its coacting member during the clamping operation, 20 and results in disarrangement of the adjusted relation between the parts, evidenced by relative tilting or rotation, or creeping, or walking, between the parts.

I have further found that such unevenness or dissimilarity can be counteracted or minimized by qualifying the clamping position or the clamping action between the respective cheeks and the coacting member to cause simultaneous or even clamping action by both cheeks, whereby rotative 30 urge between the parts is avoided, so that the relations between the clamping members are not disturbed during clamping, and the adjusted relation between the parts obtained prior to clamping is maintained after the clamping.

This is especially obvious and useful in a radial drill in which very slight variations during clamping at the inner end of the arm or sleeve are multiplied many times at the point of the drill, which point is removed from the axis on 40 which the arm swings many times the distance of the clamping cheeks from said axis.

It is the object of my invention to provide novel clamping means which maintain the clamped element in adjusted position; further, to provide 45 novel clamping means wherein the clamping effect of opposed cheeks is equalized; further, to provide novel means supplemental to the clamping means for effecting clamping without disturbance of the adjusted relation of the parts 50 clamped; and further, to provide novel means qualifying the normal relations between clamping parts to counteract disturbing movements of the clamping elements.

My invention consists in novel means for avoid-

- ing the objections hereinbefore stated; further, in a clamp bearing with an adjustable cheek or cheeks to control the clamping; further, in novel means whereby the point of the drill is maintained, after clamping, in the position to which it has been adjusted before clamping; and further, in a drilling machine in which disturbance of adjusted position of the drill is counteracted or minimized.
- 10 My invention will be further readily understood from the following description and claims, and from the drawings, in which latter:
- Fig. 1 is a front elevation of an exemplifying radial drilling machine embodying my invention.
- 15 Fig. 2 is a plan view of the same.
- Fig. 3 is a horizontal section of the same, taken on the irregular line 3—3 of Fig. 1, partly broken away.
- 20 Fig. 4 is a vertical section of the same, taken in the plane of the line 4—4 of Fig. 3, partly broken away.
- Fig. 5 is a side elevation showing my improved device applied to each cheek of the clamp, and partly broken away.
- 25 Fig. 6 is a side elevation of a first modification of my improved device, partly broken away.
- Fig. 7 is a horizontal section of the same, taken on the line 7—7 of Fig. 6, partly broken away.
- Fig. 8 is a front elevation of a second modification of my improved device, partly broken away.
- 30 Fig. 9 is a vertical section of the same, taken in the plane of the line 9—9 of Fig. 8, and partly broken away.
- Fig. 10 is a horizontal section of a third modification of my improved device, taken in the plane of the line 10—10 of Fig. 11, partly broken away.
- 35 Fig. 11 is a vertical section of the same, taken in the plane of the line 11—11 of Fig. 10, partly broken away.
- Fig. 12 is a vertical section of a fourth modification of the same, taken on a line corresponding to the line 11—11 of Fig. 10, and partly broken away.
- 40 Fig. 13 is a side elevation of a fifth modification of my improved device, partly broken away.
- Fig. 14 is an end view of the same, partly in section and partly broken away.
- Fig. 15 is a vertical section of the same, taken in the plane of the line 15—15 of Fig. 13, partly broken away; and,
- 45 Fig. 16 is a horizontal section of the same, taken on the line 16—16 of Fig. 13, partly broken away.
- 50 Fig. 17 is the exemplified drilling machine comprises a usual base 21 from which a post 22 extends rigidly upward (Figs. 1 and 2). A rotatable column 23 surrounds the post, bearings 24, 25 being located respectively between the upper portions and the lower portions of the post and column for centering the column about the post.
- 55 A drill-arm 26 has a clamp-bearing 27 about the column and extends radially outwardly from the rotatable column or sleeve. The drill-arm is provided with usual guideways 28 for slidably supporting a drill-slide 29.
- 60 A drill-spindle 30 is journaled and axially feedable and adjustable on the slide. The spindle has a usual drill 31 secured thereto.
- 65 Fig. 18 The arm is adjustable to desired elevation on the column, as by means of a usual elevating screw 34 and elevating nut 35 threaded thereto, and its clamp-bearing 27 is clamped to the column in adjusted positions by suitable clamps exemplified at 37. The drill-slide is adjustable

lengthwise of the drill-arm toward and from the column by suitable usual means, either by hand or power, and the drill-spindle is feedable up and down by usual means for coaction with the work, a piece of which is exemplified at 38, secured to the table 39 of the base.

5 The drill-arm is adjustable to various radial positions by swinging the same with its rotatable column or sleeve about the post, and is arranged to be clamped in fixed positions. The latter clamp is exemplified at 58, and as shown comprises a skirt 51, which forms part of the column or sleeve 23 and rotates therewith. The skirt is received about an enlargement 52 or stub of the post.

10 The skirt comprises cheeks 53, 54, which are shown integral with the skirt, the outer ends of the cheeks being integrally connected with the skirt (Figs. 1, 3 and 4). The lower ends of the cheeks are shown coincident with the lower end of the skirt. There are slits 55, 56 between the upper ends of the cheeks and the body of the skirt, and the inner ends of the cheeks are separated by a slit 57.

15 The inner face 61 of the skirt, including its cheeks, is normally concentric with the outer face 62 of the coacting clamping portion of the post, the latter usually having an annular groove 63 therein. The inner face of the skirt and the outer face of the coacting member are in practice 20 usually machined into cylindrical form, and when one is fitted over the other there is preferably ready relative rotation between them for permitting ready swinging of the drill-arm into desired radial positions. These concentric faces are in 25 practice normally very close together, with little play between them, so that rapid clamping effect may be had between them.

20 This clamping effect is obtained by a suitable clamping device 58 acting on the cheeks, and is 30 exemplified as including a tension-rod 65 located in bearings 66, 67 at the proximate ends of the respective cheeks. The rod may, for instance, be a threaded rod, an operating nut 68 being threaded thereto. The cheeks are drawn toward 35 each other in annular direction about said post.

25 A handle 69 is fixed to the nut for rocking the same. The inner end of the nut 68 has end contact with the bearing 67, so that, when the handle is rocked in one direction, for instance upwardly, the nut is moved axially away from the bearing 67, for separation between the bearings 66, 67 and the respective cheeks, and movement of the cheeks away from their coacting member or post, for release of the clamp and of the 40 rotatable column or sleeve, in order to permit swinging of the drill-arm.

30 Movement of the handle in the opposite direction, for instance downwardly, causes approach between the bearings 66 and 67 and the 45 cheeks, and clamping movement of the cheeks toward their coacting member or post, for causing clamping of the clamp-bearing and of the rotatable column and drill-arm to the post after adjustment thereof.

35 A limit nut 71 is threaded to the outer end of the threaded rod and is fixed in adjusted positions thereon, as by a jam-nut 72, and is for the purpose of adjustably limiting separation between the bearings 66, 67 and the cheeks for 50 unclamped relation of the clamp, and for adjusting the normal position of the handle.

40 A set-screw 73 is threaded in the bearing 66 and engages a flat face 74 on the threaded rod for preventing turning of the threaded rod. The 55

threaded rod has axial movement in its bearings for permitting adjustments and clamping.

The clamping means exemplified are illustrative, and any other usual or ordinary clamping means for effecting the clamping of the clamp-bearing may be employed, and the same may be manually operated or be operated by power.

In practice it is the custom of the operator, when he desires to drill a hole in a piece of work, to elevate the drill-arm to desired height and to clamp the bearing 27 at the inner end of the drill-arm to the rotatable column. He then adjusts the drill-slide along the drill-arm and swings the drill-arm, so that the point of the drill coincides with the point on the piece of work with which the point of the drill is to coat. After this has been done, the operator clamps the clamp 50 for fixing the column and drill-arm in adjusted radial position.

It has been found, however, that with devices of this nature as heretofore constructed, a shifting of the adjusted part, namely, of the point of the drill in the exemplification, takes place during the clamping action, with the result that the position of the adjusted part is changed from its true adjustment. This change is due to a rotative shifting or creeping of the adjusted part in the clamping operation. It is no doubt due to a quicker or more intimate contact of one of the clamping cheeks than the other with the coacting member.

I have analyzed this deflection as due to clamping, and have come to the conclusion that it is inherent in clamping mechanism as heretofore constructed. I have, therefore, provided means qualifying the clamping effect of the clamping means or the normal relative positions of the clamping parts.

I accomplish this preferably by adjusting the relative normal positions of the clamping cheeks or adjusting their relative resilience, or changing the relative clamping moments or movements or clamping effects of the same, so as to neutralize or reduce or minimize the detrimental shifting urge of the clamping means.

The shifting effect at the clamp is multiplied many times at the point of the drill, which is distanced from the axis of the rotatable column or bearing many times the distance of the contact faces between the cheeks and the post from said axis.

Whether or not axial coincidence between the axes of the clamp bearing and its coacting part is maintained during clamped and unclamped relations, the quicker or more intimate contact of one of the cheeks than the other with the coacting member, may be due to greater or more ready yield of either one of the cheeks, to a difference in atomic structure or quantity or arrangement of metal in the respective cheeks, or to other causes which may not be apparent from surface examination.

In practice the clamp bearing for fixing the inner end of the drill-arm or rotatable column to the post is usually a casting of grey iron integral with the part which rotates with the drill-arm, instanced as the rotatable column, and while in practice the coacting faces of this clamp-bearing and its coacting member are machined to accurate dimensions, the clamping effects of the respective clamp-cheeks may not be identical.

These clamping cheeks are in usual practice resilient members which are integral parts of the clamp-bearing and are normally out of clamping contact with their coacting member, and re-

quire great pressure to draw the cheeks toward each other and into intimate clamping contact with the coacting member. Variations in clamping movement, in resiliency or in moments of clamping may take place between the respective cheeks in the clamping operation.

Any such variations have a detrimental effect upon the maintenance of adjusted relation during clamping, evidenced by a greater or more ready movement of either cheek, or variation in clamping pressure between the cheeks, or of uneven applications of such pressures between the cheeks, and cause detrimental shifting of the adjusted part during the clamping operation.

Uneven contact or uneven pressure or uneven resistance to pressure between the cheeks and their coacting member during such clamping movement causes shifting of the adjusted member out of adjusted position during the clamping operation.

Rotative urge upon and rotative movement, creeping or walking of the rotatable column and the drill-arm about the post is thereby caused in drawing the skirt clamping about the post or stub.

In order to correct such variations, I have provided supplemental means wherewith to qualify the clamping action between the cheeks. I have found that such qualifying means applied to one of the cheeks is effective for correcting the evils stated, but such qualifying means may be applied to either cheek or to both cheeks, if desired. I prefer to make one of the cheeks more yieldable than the other and to apply the qualifying means to the more yieldable cheek whereby the resistances or movements of the cheeks may be equalized.

One of the cheeks may be made more yieldable than its mate by making the same thinner, but I prefer to produce such greater yield by increasing the length of one of the slits 55, 56, as note the greater length of the slit 55 in Fig. 3, thereby increasing the yielding properties of the cheek 53.

I prefer to locate the slit 57 in my improved device on the side of the column opposite the drill arm so that the overhang effect of the drill arm and slide on the clamp 50 is minimized.

The qualifying means may amplify or reduce the load upon either cheek or the relative loads between the cheeks, and may modify the relative approach between the cheeks and the coacting member, or may cause more intimate approach or less approach, or offer greater resistance or less resistance to either cheek. The dimensions of the differences are usually so small that they are not observable by the naked eye.

Referring to Figs. 1 to 4 inclusive, I provide an arm 81 between a cheek and the body of the clamp, the arm being fixed to or integral with one of said parts and provided with adjusting means for the other of said parts. It is shown fixed to the body of the skirt, as by means of bolts 82, for rigidly fastening one end of the arm to said body. This arm is preferably of steel and supplements the cheek 53. It is spaced from the cheek, as at 83.

A bolt 84 is rotatable in a bearing 85 in the other end of said arm and has threaded connection, as at 86, with the cheek 53. The head 87 of the bolt 84 forms a shoulder for the arm at one side of the arm, and the bolt may also be provided with a collar 88 fixed to said bolt, as by a pin 89, at the other side of said arm, there being a space 90 between the head and collar and the body of the arm, so that contact may be made 75

either of the head with the arm or the collar with the arm, to provide clearance in opposite direction for relative axial movement between the bolt and the arm.

- 5 The bolt 84 may be rotated for causing contact of its head with the arm and thereby urge the cheek 53 outwardly with relation to the cheek 54, or said bolt may be rotated for causing coaction between its collar 88 and the arm for causing inward urge or movement upon the cheek 53 relatively to the cheek 54.
- 10

- These respective adjustments are made, depending on the difference in resiliency or mobility or clamping effect there may be between the 15 cheek 53 and the cheek 54.

- The desired adjustment between the cheek and the arm may be readily ascertained by observing whether there is any variation from the adjusted 20 position of the adjusted member during the clamping action, and if there is any such movement, by observing the direction in which the movement takes place.

- If there is a creeping or rotative shifting movement of the point of the drill in counter-clockwise direction, the probability is that there is 25 quicker or more intimate contact of the right-hand cheek than the left-hand cheek with its coacting member, and that a corresponding compensating inward movement of the left-hand cheek is required for correcting such creeping or 30 rotative shifting.

- If there is clockwise movement of the point of the drill during the clamping action, it is probable that quicker or more intimate contact is 35 made by the left-hand cheek with its coacting member than by the right-hand cheek, and that an adjustment of the bolt 84 is advisable, which will delay or make less intimate the contact of the left-hand cheek, by adjusting the cheek 53 40 outwardly, so as to equalize its function with the function of the right-hand cheek.

- In certain relations of adjustment the resiliency of the arm supplements and in others reduces the resiliency of the cheek with which it coacts.

- 45 In Fig. 5 an arm and its attachments similar to that shown in Figs. 3 and 4 are exemplified in connection with each of the cheeks, corresponding parts of the right-hand arm being designated by similar but primed reference numerals.

- 50 In Figs. 6 and 7 I show a first modification, in which the arm and connecting parts therefor are designated by similar numerals raised to the series 100. In this exemplification the arm 181 has one end thereof fixed to the body of the skirt 55 by extending integrally therefrom, the arm being curved to correspond with the curvature of the skirt, the other end of the arm being provided 60 with the adjusting bolt 184, and its attendant parts, constructed and operating similarly to the adjusting bolt and its corresponding parts exemplified in Figs. 1 to 4 inclusive. In this instance also a similar arm and its connections is shown provided for the other cheek of the clamp-bearing.

- 65 A second modification of the arm and its connecting parts is exemplified in Figs. 8 and 9, in which the arm takes the form of a lever, similar parts of the arm and its connections being designated by similar reference numerals raised to the series 200. In this exemplification the lever 281 is pivoted on a pivot pin 201 in pivot lugs 202 of the body of the skirt.

- 70 One end of the lever is jointed to the cheek by a joint comprising a pin 203 received through a hole in the end of the lever and holes in lugs 204 on the cheek. The other end of the lever is

adjustable and has a fork 205 received in an annular groove 206 of a nut 201, having annular shoulders at the respective ends of the groove. The fork has rounded tines 208 to engage the shoulders. Adjustment of the nut qualifies the condition or position of the lever or arm. The nut has a knob 209 for rotating the same, and has threaded connection with a threaded rod 210 pivoted to the column by a pivot pin 211 received through a hole in the inner end of said threaded 10 rod and holes in pivot lugs 212 on said column.

15 The adjustment of the threaded nut has operative effect upon the arm and upon the cheek with which it has connection similar to the corresponding devices shown in Figs. 1 to 4 inclusive. A similar lever and its connections may be provided for the other cheek.

20 In each of these instances the resiliency of the arm, which is preferably of steel, may supplement the resiliency of the cheek in the clamping action, and the parts may be adjusted for either causing approach of the cheek toward its coacting face or recession of the cheek from its coacting face.

25 In the exemplification in a third modification shown in Figs. 10 and 11, the arms and connecting parts are designated by similar reference numerals raised to the series 300. In this exemplification an arm is shown for each of the cheeks, the arm and its connections for the right-hand cheek being designated by similar but primed reference numerals.

30 In this case each of the arms is fixed to the body of the skirt similarly to the structure shown in Figs. 1 to 4 inclusive, as by means of bolts 382. A bolt 384 has threaded connection in a threaded bearing 385 in the overhanging end of the arm. Its inner end is arranged to make contact with its coacting cheek for pressing the cheek inwardly, and causing outward resilient movement of the arm.

35 In this instance the resiliency of the arm supplements or qualifies the resiliency of the cheek for aiding in moving the cheek inwardly during the clamping movement, in order to equalize the 40 clamping effects between the clamping cheeks upon the coacting clamping face.

45 In a fourth modification shown in Fig. 12, similar parts are designated by similar numerals raised to the series 400. The bolt 484 has threaded connection in a threaded hole 486 in the cheek 453. Upon inward threaded movement of the bolt, the cheek 453 is urged outwardly. Each of the cheeks is preferably provided with one of these adjustments, so that each cheek may be adjusted or urged outwardly with relation to the 50 other. The resiliency of the arms supplements the resiliency of the cheeks.

55 A fifth modification is shown in Figs. 13, 14, 15 and 16, in which the relative adjustment between the cheeks is obtained by eccentric bushings located about the clamp rod. One of these bushings is shown for each of the cheeks, although one may be employed for only one of the cheeks, especially if such cheek be more yieldable than its mate, as hereinbefore explained in connection 60 with Figs. 1 to 4 inclusive.

65 In this modification similar parts are designated by similar reference numerals raised to the series 500. An eccentric bushing 513 is located in the bearing 566 of the cheek 553, and an eccentric bushing 513' is located in the bearing 567 of the cheek 554, these bearings being enlarged to accommodate the bushings. The threaded rod 565 is located in the bushings. The bushings are provided with flanges 514, 514' at 70 75

the outer ends of the bearings, the outer ends of the bushings receiving the thrusts of the units on the threaded rod.

The respective bushings are rotatively adjusted 5 in the bearings by a suitable spanner wrench the lugs of which are received in notches 515, 515' arranged about the outer peripheries of the flanges.

The adjustment of each bushing moves the 10 cheek in which it is located inwardly or outwardly with relation to its mate for adjusting the clamping relation between the cheeks. One of the bushings is provided with a segment slot 516 to accommodate the set screw 573.

15 The bushing is located in adjusted positions, as by having the outer periphery of its flange provided with teeth 517, with which the teeth of a latch 518 coat, the latch being clamped in latching position by a bolt 519 threaded into a lug 520 on the bearing in which the bushing is located.

20 It is obvious that other changes or modifications may be made in obtaining the relative adjustment between the cheeks than those herein particularly shown or described, within the scope 25 of my invention set forth in the accompanying claims.

25 My improved device is simple and effective for correcting the faults of an otherwise useful and admirable device, which is in extensive use in spite of its faults, but the faults of which have not heretofore been recognized, identified or corrected. I believe I have done this, and have therefore herein explained my invention as far as I now understand the same, and having thus fully explained my invention, what I claim as new and desire to secure by Letters Patent, is:

30 1. In steadyng means for the setting of a tool in a drilling machine, the combination with the drill-arm on which the tool is located, and 35 means for adjusting said drill-arm and the tool thereon into various radial positions of a clamp bearing for said arm comprising resilient cheeks and a part toward which said cheeks are clamped, means clamping said cheeks toward said part, and means adjusting the relative resilience between said cheeks for adjusting the relative 40 clamping moments between said cheeks and said part so that said cheeks are clamped simultaneously and equally for maintaining said clamp bearing and said part in adjusted relation throughout the clamping.

45 2. In a radial drilling machine, the combination of a post, a rotatable column adjustable about said post provided with a skirt having resilient cheeks integral therewith arranged to clamp about said post, operating means between said cheeks to clamp said cheeks, an arm between said rotatable column and a cheek, and adjusting means having operative connections 50 with said arm and said cheek adjusting the resilience of said cheek relatively to its companion cheek to equalize the resistance to flexure of said cheeks so that said cheeks are clamped simultaneously and equally about said post to maintain 55 adjusted position of said column about said post during the clamping.

60 3. In a radial drilling machine, the combination of a post, a rotatable column adjustable about said post provided with a skirt having resilient cheeks of different resiliencies integral with said skirt arranged to clamp about said post, operating means between said cheeks to clamp said cheeks, and resilient adjusting means 65 acting on the more resilient of said cheeks to decrease its resilience for adjusting the relative

normal resiliencies between said cheeks to adjust the relative clamping moments of said cheeks.

4. In a radial drilling machine, the combination of a post, a rotatable column about said post provided with a skirt having resilient cheeks of different lengths integral with said skirt arranged to clamp about said post, operating means between said cheeks to clamp said cheeks, and adjusting means acting on the longer of said cheeks for adjusting its normal resilience relative to the normal resilience of the other of said cheeks whereby to adjust the relative clamping moments of said cheeks. 10

5. In a drilling machine, the combination of an upright, a rotatable column about said upright, a clamp-bearing for the latter about said upright, a drill-arm extending outwardly from said column, a drill slide thereon, a rotatable drill-spindle on the latter arranged to support a tool, said bearing having oppositely extending resilient 15 cheeks having normal resiliencies, operating means between said cheeks to draw said cheeks toward each other and said bearing about said upright to clamp said bearing about said upright, and means adjusting the normal resiliencies between said cheeks for equalizing the resiliencies of said cheeks with relation to each other to equalize the clamping relations between said cheeks and said upright so as to steady the setting of said tool during the clamping by said 20 operating means. 25

6. In a drilling machine, the combination of an upright, a rotatable column about said upright, a clamp-bearing for the latter about said upright, a drill-arm extending outwardly from said column and arranged to be adjusted to radial positions about said upright, a drill-slide adjustable along the latter, a rotatable drill-spindle on said drill-slide arranged to support a tool, said bearing having resilient cheeks having normal resiliencies extending toward each other, operating means between said cheeks to draw said cheeks toward each other to clamp said bearing about said upright, and radially acting means changing the resiliencies between said cheeks to equalize their clamping effects upon said upright whereby to maintain the adjusted position of said column and to maintain the adjusted position of said tool between its adjustment and the clamped relation of said bearing. 35 40 45

7. In a radial drilling machine, the combination of an upright, a rotatable column about said upright, a drill-arm extending outwardly from said column and adjustable with said column to radial positions about said upright, a 55 drill-slide adjustable lengthwise of said drill-arm toward and from said column, a rotatable drill-spindle on said drill-slide arranged to support a tool, said rotatable column comprising a skirt having resilient cheeks having normal resiliencies and extending integrally therefrom toward each other about said upright, operating means between said cheeks to draw said cheeks toward each other about said upright to clamp said column thereto, an arm and adjusting means between said column and a cheek having resilient 60 action on said cheek to substantially change the resilient action of said cheek with relation to the resilient action of the other of said cheeks so that said cheeks are clamped simultaneously and equally to maintain circumferential adjusted position of said column about said support. 65 70

8. In a drilling machine, the combination set forth in claim 7, in which the adjusting means 75

operate in both of opposite directions to change the normal resilient action of said cheek.

9. In a radial drilling machine, the combination of an upright, a rotatable column about said upright, a drill-arm extending outwardly from said column and adjustable with said column to radial positions about said upright, a drill-slide adjustable lengthwise of said drill-arm toward and from said column, a rotatable drill-spindle on said drill-slide arranged to support a tool, said rotatable column comprising a skirt having resilient cheeks extending integrally therefrom toward each other about said upright, operating means between said cheeks to draw said cheeks toward each other about said upright to clamp said column thereto, resilient arms between said column and said respective cheeks, and adjusting means having operative connections with said respective arms to vary the resiliencies of said cheeks by imposing thereon resiliencies of said arms to equalize the clamping properties of said respective cheeks so that said cheeks are clamped simultaneously and equally to maintain the adjusted radial position of said drill-arm.

10. In a radial drilling machine, the combination of an upright, a rotatable column about said upright, a drill-arm extending outwardly from said column and adjustable with said column to radial positions about said upright, a drill-slide adjustable lengthwise of said drill-arm toward and from said column, a rotatable drill-spindle on said drill-slide arranged to support a tool, said rotatable column comprising a skirt having resilient cheeks extending integrally therefrom toward each other about said upright, operating means between said cheeks to draw said cheeks toward each other about said upright to clamp said column thereto, and an arm having operative connections with a rigid portion of said column and a cheek, said arm and said operative connections having resilience imposed upon the resilience of said cheek during unclamped relation of said cheek whereby to equalize the relative clamping relations between said cheeks and said upright so that said cheeks are clamped simultaneously and equally about said upright for maintaining adjusted position of said tool during the clamping.

11. In a radial drilling machine, the combination of an upright, a rotatable column about said upright, a drill-arm extending outwardly from said column and adjustable with said column to radial positions about said upright, a drill-slide adjustable lengthwise of said drill-arm toward and from said column, a rotatable drill-spindle on said drill-slide arranged to support a tool, said rotatable column comprising a skirt having resilient cheeks extending integrally therefrom toward each other about said upright, operating means between said cheeks to draw said cheeks toward each other about said upright to clamp said column thereto, and arms having operative connections with rigid portions of said column and said respective cheeks, said arms and said operative connections respectively having resiliencies imposed upon the resiliencies of said respective cheeks during unclamped relations of said cheeks whereby to equalize the relative clamping relations between said cheeks and said upright so that said cheeks are clamped simultaneously and equally about said upright for maintaining adjusted position of said tool during the clamping.

12. In a metal working machine, the combina-

tion of a machine part comprising a bearing and a coacting member having adjustment between them, said bearing provided with resilient clamping cheeks, means forcing said cheeks toward each other and toward said coacting member for clamping said bearing to said coacting member, and an arm and adjusting means having resilient properties and located between said bearing and a cheek thereof qualifying the normal resilience of said cheek and equalizing the resiliencies between said cheeks so as to clamp said cheeks simultaneously and equally to said coacting member to prevent circumferential movement between said bearing and said coacting member during the clamping.

13. In a metal working machine, the combination of machine parts comprising a bearing and a coacting member having rotary adjustment between them, said bearing provided with resilient clamping cheeks, clamping means to clamp said cheeks to said coacting member, and means adjusting the normal clamping moment of a cheek with relation to the clamping moment of its mating cheek to equalize the clamping moments between said cheeks for simultaneously and equally clamping said cheeks to said coacting member.

14. In steady means for the setting of a tool in a drilling machine in which the tool is mounted on a radial arm adjustable angularly to various radial positions and a clamp bearing is employed to clamp the radial arm in adjusted radial positions, the combination of the bearing comprising resilient clamping cheeks, clamping means for said cheeks, and a substantial resilient arm having connection with a cheek mentioned in manner to impose substantial stress upon said cheek to equalize the clamping actions of said cheeks so that the cheeks are clamped simultaneously and equally to prevent angular movement of the radial arm throughout the clamping movement of the clamping means.

15. In steady means for the setting of a tool in a drilling machine in which the tool is mounted on a radial arm adjustable angularly to various radial positions and a clamp bearing is employed to clamp the radial arm in adjusted radial positions, the combination of the bearing comprising resilient clamping cheeks, clamping means for said cheeks to clamp said bearing, and substantial means acted on by said clamping means in manner to forcefully shift the normal clamping position of a cheek mentioned so that said cheeks are clamped simultaneously and equally to prevent angular movement of the radial arm throughout clamping movement of the clamping means.

16. In steady means for the setting of a tool in a drilling machine in which the tool is mounted on a radial arm adjustable angularly to various radial positions and a clamp bearing is employed to clamp the radial arm in adjusted radial positions, the combination of the bearing comprising resilient clamping cheeks projecting toward each other, a clamping rod between the proximate ends of said cheeks, a bushing on one of said proximate ends having a bearing portion in which said clamping rod is mounted, and means for adjusting said bushing to adjust said bearing portion in a crosswise direction to adjust the normal lateral position of the cheek on which said bushing is located in manner to impose substantial lateral stress on said last-named cheek during clamping action of said clamping rod so that the cheeks are clamped simultaneously and

equally to prevent angular movement of the radial arm throughout the clamping.

17. In steadyng means for the setting of a tool in a drilling machine, the combination with the drill-arm on which the tool is located and means for adjusting said drill-arm and the tool thereon into various radial positions, of a clamp bearing for said drill-arm comprising clamping cheeks having normal clamping properties and a part toward which said cheeks are clamped, clamping means clamping said cheeks toward said part, and means adjusting the clamping properties between said cheeks so that said cheeks are clamped simultaneously and equally toward said part to maintain said drill-arm and said tool in adjusted radial position throughout the clamping movement of said clamping means.
18. In steadyng means for the setting of a tool in a drilling machine in which the tool is mounted on a radial arm adjustable angularly to various radial positions and a clamp bearing is employed to clamp the radial arm in adjusted radial positions, the combination of the bearing comprising clamping cheeks having normal clamping properties and a part toward which said cheeks are clamped, clamping means clamping said cheeks toward said part, and means acting laterally on a cheek to adjust the clamping properties between said cheeks so that said cheeks are clamped simultaneously and equally toward said part to maintain said drill-arm and said tool in adjusted radial position during the clamping movement of said clamping means.
19. In a metal working machine employing a clamp bearing and a coacting member having rotative adjustment between them, the combination of the clamp bearing provided with resilient cheeks extending toward each other, clamping

means between said cheeks to clamp said bearing to said coacting member, and means adjusting the resilience of a cheek mentioned with relation to its companion cheek in manner to equalize the resistance to flexure of said cheeks by said clamping means so that said cheeks are clamped simultaneously and equally to maintain said rotative adjustment throughout clamping movement of said clamping means.

20. In a metal working machine employing a clamp bearing and a coacting member having rotative adjustment between them, the combination of the clamp bearing provided with resilient cheeks extending toward each other, clamping means between said cheeks to clamp said bearing to said coacting member, and means adjusting a cheek mentioned adjusting its normal distance from said coacting member and its normal resilience with relation to its companion cheek so that said cheeks are clamped simultaneously and equally to said coacting member to maintain said rotative adjustment throughout clamping movement of said clamping means.

21. In a metal working machine, the combination of a clamp bearing and a coacting member having rotative adjustment between them, said bearing provided with resilient cheeks extending toward each other, clamping means between said cheeks to clamp said cheeks to said coacting member, means adjusting the resilience of a cheek mentioned in manner to equalize the clamping moments and stresses of said cheeks upon said coacting member so that said cheeks are clamped simultaneously and equally to maintain the rotative adjustment made between said bearing and said coacting member throughout clamping movement of said clamping means.

JACK C. CARLTON.
